(57) **CLAIM**

The ornamental design for measuring apparatus, as shown and described.

DESCRIPTION

FIG. 1 is a perspective view of a measuring apparatus showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a further perspective view thereof.

The broken lines shown in the figures are included for the purpose of illustrating portions of the measuring apparatus that form no part of the claimed design.
